BY
Watson E. Cobeman
ATTORNEY.

UNITED STATES PATENT OFFICE.

HARVEY SEWARD, OF PETERSBURG, VIRGINIA.

TRUNK.

Application filed July 11, 1923. Serial No. 650,896.

To all whom it may concern:

Be it known that I, HARVEY SEWARD, a citizen of the United States, residing at Petersburg, in the county of Dinwiddie and State 5 of Virginia, have invented certain new and useful Improvements in Trunks, of which the following is a specification, reference being had to the accompanying drawings.

This invention relates to certain improvements in trunks and it is primarily an object 10 of the invention to provide a novel and improved device of this general character which is particularly adapted for transportation by automobile or other vehicle and 15 which is provided with means whereby ready and convenient access may be had therein.

Another object of the invention is to provide a novel and improved device of this general character embodying a main trunk 20 section having associated therewith a swinging section to facilitate access within the main trunk section and wherein said swinging section has fixedly secured thereto a tray or box together with a removable tray 25 or box insertable within the main trunk section.

An additional object of the invention is to provide a novel and improved device of this general character wherein is comprised 30 a removable tray or box together with means for maintaining the removable tray or box in substantially a fixed position when the trunk is closed.

Furthermore it is an object of the invention to provide a novel and improved trunk of this general character comprising a main section having associated therewith a hinged end section, one side of the hinged section and the adjacent portion of a side 40 of the main trunk section being open together with a closure section common to both the open side of the hinged section and the open portion of the main trunk section.

The invention consists in the details of construction and in the combination and arrangement of the several parts of my improved trunk whereby certain important advantages are attained and the device rendered simpler, less expensive and otherwise 50 more convenient and advantageous for use, as will be hereinafter more fully set forth.

The novel feature of my invention will hereinafter be definitely claimed.

In order that my invention may be the better understood, I will now proceed to de-

scribe the same with reference to the accompanying drawings, wherein:—

Figure 1 is a view in perspective of a trunk constructed in accordance with an 60 embodiment of my invention;

Figure 2 is a view in perspective of my improved trunk as herein disclosed with the hinged end section and the closure end section in open position; 65

Figure 3 is a vertical sectional view taken through the trunk as illustrated in Figure 1;

Figure 4 is a horizontal sectional view taken substantially on the line 4—4 of Figure 3; and 70

Figure 5 is a fragmentary vertical sectional view taken through the central portion of Figure 2 with the removable tray or box omitted. 75

As disclosed in the accompanying drawings, S denotes the main section of the trunk provided with a top or cover section T hingedly connected as at 1 to the rear wall 2 of the section S. The upper portion 80 of the front wall 3 of the section S is open and the portions of the side walls 4 contiguous to the open portion are of a width less than the width of the remaining portions of said side walls, the top or cover section 85 T being of a width equal to the reduced portions of the side walls 4.

Hingedly connected as at 5 with the inner or upper marginal portion of the front wall 3 of the trunk section S is a swinging 90 front section A which coacts with the top or cover section T to close the trunk, said section A being common when closed, to both the trunk section S and the top or cover section T as is particularly illustrated in 95 Figures 1 and 3 of the accompanying drawings.

The free end of each of the side walls 4 is provided with a flange 6 which coacts with and overlaps an outstanding flange 7 100 carried by an end wall of the cover or top section T while the adjacent end of the rear wall 2 is provided with a flange 8 which overlaps the rear wall of the cover or top section T when said section is in closed 105 position. The outer free longitudinal marginal portion of each of the side walls 4 is also provided with an outstanding flange 9 which overlies the side walls of the section A when said section is in closed position. 110 The overlapping of these various parts, when the trunk is closed results in a dust-

proof and water-proof closing whereby the contents of the trunk are effectively protected.

Each of the side walls of the section A is provided at predetermined points thereon and at its inner or hinged end portion with the dowel pins 10 which engage the sockets or escutcheon plates 11 suitably positioned upon the adjacent side wall 4 of the main trunk section S, the outermost dowel 10 engaging a socket or escutcheon plate 12 carried by the adjacent portion of an end wall of the top or cover section T. By this means the sections T and A are effectively maintained in closed position, but in order to positively lock the same against opening movement I provide the sections T and A with the coacting hasps and lugs as indicated at 14 and also with a key controlled locking means as indicated at 15, said key controlled locking mechanism being of any type or character preferred.

Fixedly secured by the rivets 16 or the like within and to the inner face of the section A is a box or tray 17 provided with a cover or lid 18 hingedly connected as at 19 to the side wall 20 of the box or tray 17 adjacent to the hinged connections 5 so that when the section A is in its full open position as illustrated in Figure 2, the lid 18 swings upwardly into open position. The lid 18 is locked in closed position in any conventional manner as indicated at 21. Disposed along the free marginal portions 35 of the side walls 4 of the section S are the inwardly directed cleats 22, the inner or lower end of each of said cleats being continued by a second cleat 23 spaced a distance from the front wall 3 of the section S materially less than the extent of reduction of the reduced portion of the associated side wall 4 and the end portion of said cleat 23 immediately adjacent to the cleat 22 is disposed on a bevel as at α toward the outer face of the cleat 22, said outer face of the cleat 22 being substantially a continuation of the bevel α . The bevel α has disposed thereover a wear plate 25 preferably of metal.

50 B denotes a removable box or tray having opposite marginal portions of one face wall extended to provide the flanges 26 to engage within the guide ways 27 provided between the cleats 23 and the adjacent front wall 3, the extent of insertion of the box or tray B within the section S being limited by contact of said applied box or tray with a suitably positioned spaced cleat 28 secured to the inner face of the front wall 3, as is particularly illustrated in Figure 3.

55 The cleat 28 is preferably so positioned that when the box or tray B is applied within the section S, the outer wall of said box or tray B will be substantially flush with the upper or free margin of the front wall

3 or more particularly the flange 29 extending therebeyond and which flange 29, when the section A is in closed position, serves to provide a dust-proof and water-proof joint. The box or tray 17 carried by the hinged section A is so positioned that when the section A is closed, the side wall 20 or that wall adjacent to the hinged connections 5 is arranged closely adjacent to the box or tray B whereby said box or tray B is maintained substantially fixed within the section S so that the same will not be subjected to independent vibration during the handling of the trunk or when the trunk is in transit.

When the box or tray B is applied within the guide ways 27 the flanges 26 will come in contact with the bevel α of each of the cleats 23 and thereby force the tray or box B in a direction toward the wall 3 and in a manner whereby the flanges will have close frictional contact with the flange 29 at the lower portion of each of the bevels α and with the wall 3 immediately adjacent to the cleat 28. By this particular arrangement the box or tray B when applied, is further held against undue movement toward or from the wall 3 so that the contents thereof are further protected against undue vibration during handling of the trunk or when the trunk is in transit.

55 In applying the tray or box B the cleats 22 serve as guides to facilitate the requisite insertion of said box or tray B in a manner which is believed to be self-evident.

From the foregoing description it is thought to be obvious that a trunk constructed in accordance with my invention is particularly well adapted for use by reason of the convenience and facility with which it may be assembled and operated, and it will also be obvious that my invention is susceptible of some change and modification without departing from the principles and spirit thereof and for this reason I do not wish to be understood as limiting myself to the precise arrangement and formation of the several parts herein shown in carrying out my invention in practice except as hereinafter claimed.

It will be seen that the uppermost or outermost escutcheon plate 11 carried by the swinging front section A is a double plate. That is to say, it is provided with two dowels and it is so positioned that when the swinging section A and the top T are in closed position one of these dowels will be received in a socket member carried by the top whereby the joint between the main or body section S, the swinging section A, and the top T, is made a strong one well capable of withstanding the rough usage to which a trunk is sometimes put.

115 In defining the relative positions of the various sections or parts as comprised in my improved trunk it is to be understood that

the same is done with the trunk in the position illustrated in Figures 1 and 2 of the drawings or when the trunk is in its preferred position to apply articles therein or 5 to remove them therefrom.

I claim:

1. A trunk comprising a main section having the upper portion of its front wall open, a swinging section hingedly connected 10 with the upper portion of the front wall and designed in closed position to close the open portion of said front wall, a removable box insertable within the main trunk section through the open portion of said front wall, 15 and a box carried by said swinging section on the inner wall thereof, designed to extend over said removable box in the closed position of said swinging section to hold the removable box in place.
2. A trunk comprising a main section having the upper portion of its front wall open, a swinging section hingedly connected to the main section and adapted to close the open portion of said front wall, a removable 25 box insertable in the trunk through the open portion of said front wall, cleats carried by the main section of the trunk and spaced from the front wall thereof, said removable box being provided with flanges receivable 30 in the spaces between said cleats and the said front wall, and a box carried by the swinging section on the rear wall thereof and adapted in closed position of said swinging member to extend over the removable 35 box as and for the purpose set forth.
3. A trunk comprising a main section having the upper portion of its front wall open, vertically disposed cleats in the lower portion of said section and spaced from the front wall thereof, a removable box insertable 40 in said main section through the open wall thereof and provided with side flanges insertable between said cleats and the said front wall, a swinging section hingedly connected to the front wall of the main section, a box carried by said swinging section 45 on the rear wall thereof and adapted in the closed position of said swinging section to extend over the top of the removable box to hold the latter in place, and a horizontally 50 disposed cleat secured to the rear face of the front wall of the main section above the bottom of the latter and upon which said removable box is adapted to rest.
4. A trunk comprising, in combination, 55 a main trunk section having an end portion of a wall thereof open, a swinging trunk section hingedly connected to said wall and movable into a position to close the open portion thereof, a removable box insertable within the main trunk section 60 through the open portion of said wall, means carried by said wall for holding said box when applied, and means carried by the swinging section and coacting with the removable box when the swinging section

is closed to hold said removable box against substantial vibration.

5. A trunk comprising, in combination, a main trunk section having an end portion of a wall thereof open, a swinging 70 trunk section hingedly connected to said wall and movable into a position to close the open portion thereof, a removable box insertable within the main trunk section through the open portion of said wall, 75 means carried by said wall for holding said box when applied, and a box fixedly carried by the swinging section and closely approaching the applied removable box when the hinged section is in closed position to hold said removable box against substantial vibration.

6. A trunk comprising, in combination, a main trunk section having one wall terminating inwardly of an end of the trunk 85 to provide an entrance opening, inwardly directed cleats secured to the side walls of the trunk section contiguous to the opening and inwardly spaced with respect to said first wall, additional cleats secured to the side walls of the trunk section and spaced from the first wall a distance less than the spacing of the first named cleats, the end portions of the second named cleats 90 adjacent to the first named cleats being beveled in a direction toward the first named cleats, the second named cleats coacting with the first named wall to provide guide ways, a box insertable within the trunk section and provided with oppositely disposed 95 flanges for contact with the first named cleats to engage within the guide ways.

7. A trunk comprising, in combination, a main trunk section having one wall terminating inwardly of an end of the trunk 105 to provide an entrance opening, inwardly directed cleats secured to the side walls of the trunk section contiguous to the opening and inwardly spaced with respect to said first wall, additional cleats secured to the side walls of the trunk section and spaced from the first wall a distance less than the spacing of the first named cleats, the end portions of the second named cleats 110 adjacent to the first named cleats being beveled in a direction toward the first named cleats, the second named cleats coacting with the first named wall to provide guide ways, a box insertable within the trunk section and provided with oppositely disposed 115 flanges for contact with the first named cleats and to engage within the guide ways, and means carried by the first named wall for limiting the extent of travel of the box within the guide ways.

8. A trunk comprising, in combination, a main trunk section having one wall terminating inwardly of an end of the trunk to provide an entrance opening, inwardly directed cleats secured to the side walls of 130

the trunk section contiguous to the opening section and provided with oppositely disposed flanges for contact with the first named first wall, additional cleats secured to the side walls of the trunk section and spaced 5 from the first wall a distance less than the spacing of the first named cleats, the end portions of the second named cleats adjacent to the first named cleats being beveled in a direction toward the first named 10 cleats, the second named cleats coacting with the first named wall to provide guide ways, a box insertable within the trunk sec- 15 and means carried by the first named wall for limiting the extent of travel of the box within the guide ways, said second named cleats operating to impose frictional resistance to the applied box. 20

In testimony whereof I hereunto affix my signature.

HARVEY SEWARD.
